PUMP JACK

Karl T. Blakeley, Wills Point, Tex.

Application December 9, 1940, Serial No. 369,345

6 Claims. (Cl. 74—31)

This invention relates to pump jacks but may be utilized in other machinery where it is desired to convert rotary motion into reciprocating motion without undue hammering at the ends of the reciprocal strokes.

An object of the invention is to provide an improved pump jack of simplified construction, in which rotary motion is converted into reciprocating motion smoothly and without undue noise or friction.

A further object of the invention is to provide an improved pump jack in which the arrangement of parts is such as to avoid undue wear.

The invention consists in the novel construction, arrangement, and combinations of parts, as hereinafter more specifically described and claimed.

Two sheets of drawings accompany this specification as part thereof, in which like reference characters indicate like parts throughout.

Figure 1 is a front elevation of the improved jack showing the head at the end of the up stroke;

Figure 2 is a transverse vertical cross section taken on line 2—2 of Figure 1;

Figure 3 is a fragmentary front elevation of the upper end of the head shown approaching the bottom of a stroke;

Figure 4 is a view similar to Figure 3 as the heads starts the up stroke;

Figure 5 is a fragmentary enlarged view of the bottom part of the pump head at the end of its up stroke;

Figure 6 is a horizontal cross sectional view taken on line 6—6 of Figure 4.

In accordance with the present invention the improved jack comprises a frame consisting of a base 1 with vertical spaced parallel columns 2, each having on its inner face a track 3. The columns 2 are preferably spaced by transverse frame members 4 to assure their alignment.

Between the columns 2 is slidably positioned a head 5 having on its parallel side edges grooves 8 adapted to receive tracks 3. The head is engaged by any conventional means with the pump rod 9. The head 5 is provided with an elongated opening having spaced parallel side walls 6—6 connected by curved end walls 7—7 and all the inner walls of this opening are provided with rack teeth and constitute an endless rack.

On the front and rear faces of the head are peripheral flanges 20 constituting guide tracks. These tracks are interrupted on each side near the top and bottom by cross-over clearances 21 for a purpose hereinafter explained.

A transverse frame member 10 is carried by the columns 2—2, provided with journals for a drive shaft 11, upon which is fixedly secured a gear 12 and upon which is also pivotally mounted a rock frame 13 which, as illustrated, consists of two spaced strap members, positioned one on either side of fixed gear 12, and between which are journaled gears 14—15, and 16. It will be noted that gear 16 engages directly with fixed gear 12 and also with one side of the endless rack, while gear 14 at the opposite end of rock frame 13 engages the opposite side of the rack and is driven through intermediate gear 15 from fixed gear 12. It will thus be seen that the rack engaging gears 14 and 16 are both driven from fixed gear 12, but in opposite directions. It will further be noted that the rock frame 13 is longer than the distance between the parallel sides of the rack by reason of which it will always assume an oblique position with respect to those parallel sides of the rack with one or the other of the rack engaging gears in advance of the other rack engaging gear.

Pivotally mounted on the outer ends of rock frame 13 are rollers 18 adapted to engage the outer face of flanges 20 and thus secure gears 14 and 16 in engagement with the rack.

By reason of the construction thus described it will be apparent, reference being had to Figures 3 to 5, that the head being at the end of its downward stroke, as illustrated in Figure 3, gear 16 being in advance will be forced from the side of the rack as gear 14 starts to traverse the upper curved portion of the rack, the guide rollers 18 adjacent gear 16 passing through the adjacent cross over 21 and thus rocking the rock frame 13 until gear 14 engages the opposite side as shown in Figure 4 whereupon the head will commence its up-stroke. In Figure 5 the head is shown completing the end of its up-stroke with gear 14 again engaging the side of the rack, the adjacent rollers 18 having passed out through adjacent cross-over clearances 21.

It will be noted that the rock frame 13 is held constantly in position with respect to the head by means of rollers 18 and guide flange 20 at one end or the other of the rock frame and during the greater part of the vertical stroke of the head by the rollers on both ends, but that the cross-over gaps 21 provided in flange 20 permit the rocking of the rock frame at each end of its stroke.

Various modifications will readily suggest themselves to those skilled in the art and it will be apparent that the present invention, while

shown applied specifically to pump jacks may be of equal utility in connection with various other machinery, where the same or similar problems are presented.

Having thus fully described my invention, I claim:

1. A frame, a member reciprocable in the frame having an interior endless rack comprising spaced parallel sides connected at each end with curved parts, a shaft extending within and perpendicular to the plane of the rack, a driving gear fixed to the shaft, a rock frame pivotally mounted on the shaft, and gears mounted on said pivoted frame driven from said fixed gear and including two oppositely disposed gears adapted to engage the opposed parallel rack sides and to be driven in opposite directions, and means for maintaining the rock frame in operative association with the frame at all times.

2. An elongated endless rack having spaced parallel sides and curved ends with teeth formed on the inner face, and means for reciprocating the rack comprising a shaft passing within the rack, a frame pivoted on the shaft, a gear fixed on the shaft and a plurality of gears pivotally mounted on the frame including two driven gears adapted to engage the opposite parallel sides of the rack and rotate in opposite directions.

3. A pump jack comprising a base and two parallel vertical frame members each having a track on its inner face, a reciprocating head slidably engaging said tracks and formed with an opening having spaced parallel side walls and curved top and bottom walls, said inner walls provided with teeth to constitute an endless rack, a shaft extending between and supported from the frame members and passing through the opening in the head, a gear fixed on the shaft, a rock frame pivoted on the shaft, a plurality of gears rotatably mounted on the frame including two driven gears adapted to engage the opposite parallel rack walls of the head and to be rotated in opposite directions, means for maintaining the rock frame in operative relation to the head and means for connecting the head with the pump rod.

4. Means for translating rotary motion into reciprocating linear movement comprising a shaft, a gear fixed on the shaft, a rock frame pivoted on the shaft, a plurality of gears rotatably mounted on the rock frame including gears at the ends of the rock frame and on opposite

sides of the shaft arranged to be driven in opposite directions by said gear fixed on the shaft, an endless rack surrounding said rock frame including two parallel straight sides connected by curved end parts, said end driven gears arranged to engage the parallel sides of the rack simultaneously and said frame adapted to be rocked at the ends of said straight sides, a guide track on the rack having cross-over spaces at top and bottom and rollers on the ends of the rock frame engaging said track.

5. A frame, a member reciprocable in the frame formed with an opening having parallel straight sides connected by curved ends, the inner walls 15 of said opening formed with teeth constituting an endless rack, a shaft passing through said opening, a gear fixed on the shaft, a rock frame longer than the distance between the straight sides of the rack, a plurality of gears rotatably 20 mounted on the rock frame including a gear at each end and on opposite sides of the fixed gear arranged to be driven in opposite directions by said gear and to engage the opposite straight sides of the rack, and cooperating means on the 25 frame and rock frame to maintain same in operative relation.

6. A pump jack comprising a base and two spaced parallel frame members each having a track on its inner face, a reciprocating head 30 slidably engaging said tracks and formed with an opening having parallel side walls and curved top and bottom walls, said inner walls provided with teeth to constitute an endless rack, a peripheral guide track on said head having spaced 35 cross-over gaps, a shaft extending through the opening in the head, journals for the shaft carried by the frame, a gear fixed on the shaft, a rock frame longer than the distance between the parallel rack sides pivoted on the shaft, gears 40 pivoted on the rock frame on opposite sides of the fixed gear, one of said gears meshed with the fixed gear and the rack on one side and another gear meshed with the rack on the opposite side and through an intermediate gear with the fixed 45 gear whereby the rock engaging gears will be driven from the fixed gears in opposite directions and rollers on the rock frame adapted to engage the peripheral guide track and maintain said rock frame in constant operative relation to the head while permitting the rocking of the rock frame.

KARL T. BLAKELEY.
